(57) **CLAIM**

The ornamental design for an attachment for massage device as shown and described.

DESCRIPTION

FIG. 1 is a top front isometric view of an attachment for massage device showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom front isometric view thereof.

The broken lines in the figures show portions of the attachment for massage device that form no part of the claimed design.

1 Claim, 5 Drawing Sheets
